Des. 211,349
Patented June 11, 1968

211,349

ELECTRIC LAMP

Thomas Hammond, Cobham, Surrey, England, assignor
to Rival Lamps Limited, Weybridge, Surrey, England,
a British company

Filed June 9, 1966, Ser. No. 2,618

Claims priority, application Great Britain Dec. 23, 1965

Term of patent 14 years

(Cl. D26—8)

Fig. 1.

Fig. 2.

Fig. 3.

FIGURE 1 is a front elevational view of an electric lamp, showing one form of my new design wherein the lamp has one filament;

FIGURE 2 is a bottom plan view of the form shown in FIGURE 1;

FIGURE 3 is a side elevational view of the form shown in FIGURE 1;

FIGURE 4 is a front elevational view of an electric lamp, showing a second form of my new design wherein the lamp has two filaments;

FIGURE 5 is a bottom plan view of the form shown in FIGURE 4; and

FIGURE 6 is a side elevational view of the form shown in FIGURE 4.

The dominant features of my new design are shown in solid lines in the drawing.

I claim:

The ornamental design of an electric lamp, substantially as shown and described.
